UNITED STATES PATENT OFFICE.

CHARLES M. FAIRBANKS, OF HARTFORD, CONNECTICUT, ASSIGNOR TO
ELIAS A. WILKINSON, OF NEWARK, NEW JERSEY.

INDEX-PLATE FOR SEWING-MACHINES.

SPECIFICATION forming part of Letters Patent No. 268,651, dated December 5, 1882.

Application filed June 19, 1882. (No model.)

To all whom it may concern:

Be it known that I, CHARLES M. FAIRBANKS, of Hartford, Connecticut, have invented a new and useful Index-Plate for Sewing-Machines, 5 as set forth in this specification and the drawings thereof.

Figure 1 is a front view of the invention. Fig. 2 is a view of the same applied to the arm of a sewing-machine. Fig. 3 is a detailed view 10 of a portion of a sewing-machine to be used therewith.

The invention relates to the feed mechanism; and it consists in combining with one of the levers thereof an index-plate to indicate the size of needle and thread adapted to the 15 length of stitch when the adjustable fulcrum is in any position desired.

In the form of construction shown the index-plate A has a lengthwise slot, B, to receive the set-screw C, connected to the adjustable fulcrum D on the vertical lever E, which imparts motion from the main shaft to the feed that moves the goods in sewing. The index-plate is numbered on one side of the slot, 25 1, 2, 3, 4, 5, 6, 7, 8, at intervals, to indicate the size of needle required when the set-screw C is opposite any particular number. The index-plate is also numbered on the other side of the slot, 8 to 12, 16 to 24, 30 to 36, 40 to 50, 60 to 30 70, 80 to 90, 100 to 150, 200 to 300, at intervals, to indicate the size of thread to be used when the set-screw C is opposite any particular numbers.

By moving the set-screw C up or down in the 35 slot B the adjustable fulcrum D is moved on the vertical feed-lever E, and consequently the motion of the feed is changed, which causes the fabric to be moved at a greater or less distance at each stitch, and the length of the stitch to 40 be changed accordingly, which requires a corresponding change on the sizes of the needle and thread, as indicated in the index-plate.

Before my invention indices were not new in connection with a spring-feed to indicate

the number of stitches to the inch, and a separate scale was not new to indicate the size of thread and needle to be used for the purpose; but my improvement is an index-plate combined with an adjustable fulcrum or stitch-regulating mechanism, to indicate the size of needle and thread to be used with the adjustable fulcrum or stitch-regulating mechanism in any position, as indicated by a set-screw or holding device on the index-plate to hold the adjustable fulcrum or stitch-regulating mechanism in place.

The details of construction and operation may be varied from that shown and described within the scope of my improvement. For example, the index-plate and adjustable fulcrum 60 may be combined with the horizontal feed-lever.

I claim as my invention—

1. The combination, in a sewing-machine, of a set-screw, C, connected to an adjustable fulcrum, D, on a vertical feed-lever, E, and an index-plate, A, having numbers 1, 2, &c., to indicate the size of needle, and numbers 8 to 12, &c., to indicate the size of thread, adapted to the length of stitch determined by the movement of the feed in any position of the set-screw and adjustable fulcrum, substantially as set forth.

2. The combination, in a sewing-machine, of an external holding device connected to an adjustable fulcrum on one of the feed-levers, and an index-plate having numbers to indicate the size of needle, and numbers to indicate the size of thread adapted to the feed in any position of the holding device and adjustable fulcrum, substantially as set forth.

In testimony whereof I hereunto subscribe my signature in the presence of two attesting witnesses.

CHARLES M. FAIRBANKS.
